SPOOLER

Irving C. Howes, North Andover, Mass., assignor
to Davis & Furber Machine Company, North
Andover, Mass., a corporation of Massachusetts

Application November 20, 1947, Serial No. 787,231

14 Claims. (Cl. 28—32)

1

This invention relates to a spooler employed in winding a plurality of yarn ends onto a large spool of the type in which the yarn mass being wound rests upon a driven drum and is wound thereby onto the spool.

The object of the invention is to provide such a spooler adaptable to a wide range of conditions and readily adjustable to run at high speed and as high a speed as the conditions of the yarn prevailing will warrant.

The object of the invention is further to provide such a spooler which may readily and easily be handled by the operative and in which all controls and adjustments are easily reached and manipulated.

The object of the invention is further to provide means for positively feeding the yarn ends to the spool so as to relieve the spool from the strain of drawing the yarn ends from the creel or other supply, and further to provide means for readily and accurately controlling the tension of the yarn ends as they pass to the spool.

The object of the invention is further to provide means for maintaining a constant pressure of the spool against the drum during the winding operation so as to secure, especially in connection with the control of the tension, an evenly compacted mass of yarn.

The object of the invention is further to provide power operated means, more particularly fluid operated means, and specifically compressed air operated means for maintaining the constant required pressure of the yarn of the spool against the drum during the winding operation, and also for raising and doffing the wound spool, and also for placing an empty spool in winding position.

The object of the invention is further to provide a novel track supporting structure both for the wound spools and the empty spools so positioned as to enable the ready reception of the doffed wound spools and the ready replacement of the empty spool.

These and other objects and features of the invention will appear more fully from the accompanying description and drawings and will be particularly pointed out in the claims.

The drawings illustrate a preferred form of construction embodying the various features of the invention and in which compressed air is employed, as is preferred, in the power operated means for controlling the pressure of the spool on the drum and for controlling the doffing of the wound spool and the replacement of the empty spool. The spooler is shown further as

5 of that type in which each yarn end is vibrated as it is wound so that each end winds into an individual cheese or disk on the spool, thus enabling any number of these cheeses or disks to be removed from the spool in connection with subsequent operations such as warp beaming.

10 The spooler may, of course, be made of any standard size and of the usual materials employed in such an apparatus. It is necessary, therefore, only to describe in detail those features of the apparatus with which this invention is particularly concerned, other features of the construction being well known and familiar to those skilled in the art.

15 In the drawings:

Fig. 1 is a view in perspective looking toward the front and left hand side of a spooler embodying a preferred form of the invention;

20 Fig. 2 is a detail in front elevation illustrating the means for vibrating the yarn ends as they are wound;

25 Fig. 3 is a view of the spooler in front elevation with the main casing removed;

Fig. 4 is a top plan view with the casing removed and with the central portion of the spooler broken away;

30 Fig. 5 is a view in left hand side elevation with the casing removed showing the elements in position at the beginning of the winding operation;

Fig. 6 is a view similar to Fig. 5 showing the elements in position at the end of the winding operation;

35 Fig. 7 is a detail top plan view and partially in section showing the construction at the left hand end of the feed and cooperating rolls with the means of adjusting the latter roll;

40 Fig. 8 is a view in side elevation of a portion of the elements showing the position when the ends are being tied on the wound spool and the spool is about to be doffed;

Fig. 9 is a similar view showing the elements in position as the empty spool is being placed in the spool supports and before the spool has been moved down to winding position; and

45 Fig. 10 is a view in section illustrating an adjustable pulley for varying the speed of the feed roll.

The main portion of the machine is supported by a suitable frame with a casing enclosing the gears, belts and other elements located at the sides, and also the motor, piping, electronic stop motion controlling mechanism and other features conveniently located at the bottom of the machine.

50 This frame, which may be of any suitable con-

struction for the purpose, comprises the side frame members 1 and 2 in which are journaled the various shafts and upon which are conveniently mounted other elements of the machine as hereinafter set forth.

The ends of yarn drawn from a suitable creel or other supply support pass through separate thread guides at the front of the machine, under and around the measuring and feed roll, over the cooperating adjustable top roll, through the drop wires of a stop motion mechanism, thence through a vibrating thread guide and wind on to the jack spool held with the required pressure by a novel feature of this invention against the surface of the winding drum.

The winding drum 3 is of the usual construction and is carried by a shaft 4 journaled in suitable bushings in the side frame members 1 and 2. At the right-hand end it is provided with a pulley 5 preferably driven by a belt 6 from a pulley 7 mounted on the shaft 8 of an electric motor 9 located beneath the machine. The other elements of the machine are preferably driven from the shaft 4 of this winding drum. The speed of rotation of the drum 3, and consequently the speed with which the machine is operated, is adjustable and in this case this adjustability of the speed is preferably secured by varying the speed of the motor. For this purpose a knob 10 is shown at the right-hand side of the machine acting through a suitable rheostat 11 to adjust the speed of the motor as required.

As best seen in Figs. 5 and 7 the ends 12 of the yarn lead from a suitable creel or other supply through, and are maintained separated by, self-threading guide eyes 13 mounted in a flat blade 14 at the front of the machine. This blade extends at each end, and is pinned, into bushings 15 rotarily adjustable in the side frame members 1 and 2 so that the position of the guide eyes may be adjusted as required.

The measuring feed roll 16 is secured to a suitable shaft 17 journaled at its ends in the side frame members and is shown as driven at the left-hand side by a pulley 18. The cooperating adjustable top roll 19 is carried by a shaft 20 journaled in the ends of arms 21 which arms are journaled on the bushings 15. The arms 21 are provided with lugs 22 in which are mounted vertical set screws 23 seated on projections 24 from the side frame members. Thus the top roll 19 may be accurately adjusted with respect to the feed and measuring roll so as to maintain a light pressure on the yarn ends and give the light pinching action necessary for securing the proper feeding action and maintaining the proper tension on the yarn ends.

From the feeding and measuring roll with its cooperating adjustable top roll, the yarn ends preferably pass through the drop wires of a suitable stop motion mechanism as shown in Fig. 4. These drop wires 25 may be of a generally familiar type straddling a metal bar 26 insulated at the sides and mounted at its ends in brackets 27 secured to the side frame members. At each side of and spaced from this bar 26 are the usual parallel supporting bars 28 also mounted in the brackets 27. When an end breaks, the drop wire supported thereby makes an electric contact with the bar 26 closing a circuit extending in this case to an electronic stop motion mechanism 29 which may be of a standard type and which functions automatically and immediately to stop the rotation of the motor 9.

From the drop wires of the stop motion mecha-

nism, as best seen in Fig. 2, the ends pass through the guide eyes 30 carried by the vibrating or longitudinally reciprocating bar 31 mounted to slide endwise in slotted brackets 32 secured to the side frame members. This bar 31 is supported in the slotted brackets 32 by a plurality of arms 33 clamped on a rod 34 extending beneath and parallel therewith and mounted to slide in the frame side members. At its left-hand end this rod 34 extends through the side frame member 1 and its end 35 engages the face of a cylindrical cam 36 and is held there-against by a spring 361. The cam is journaled on a stud shaft 37 projecting from the side frame member 1 and has secured thereto a pulley 38. Consequently when the pulley 38 is rotated, the bar 31 with the thread guides 30 is reciprocated causing each end to wind an individual disk or cheese of yarn. By providing a suitable cam these disks or cheeses may be formed with a quick or slow traverse, and any required number of ends may be taken off from the spool, some at one time and some at another as may be required.

As best seen in Figs. 5 and 6 from the thread guides 30 the yarn ends pass to the jack spool, the core 39 of which first, and then the mass of yarn as wound thereon, rests upon the surface of the driving drum 3. These spools are of the usual construction having the heads 40 spaced to straddle the ends of the driving drum.

The elements of the machine thus described are preferably driven from the main shaft 4 of the driving drum by V-shaped pulleys, and the V-shaped belts 41 and 42 cooperating therewith and with a series of V-shaped pulleys. As illustrated the belts 41 extends around the pulley 43 secured to the shaft 4, thence around an idler pulley 44 journaled on a shaft 45 adjustably mounted on the side frame member 1 so as to maintain the belt tight, thence around the pulley 38 which rotates the cam 36, thence around a pulley 46 journaled on the side frame member 1, and thence back to the pulley 43. A second pulley 47 is secured to the pulley 46 and the belt 42 extends around this pulley 47 and the adjustable pulley 18 by which the feeding and measuring roll 16 is driven.

A clock or counter 48 for measuring the yardage wound is shown as driven by a chain 49 extending around a sprocket on the shaft 17.

An important feature of the invention resides in the fact that the yarn ends are drawn from the creel by the feeding and measuring roll and its top cooperating roll and are thus fed thereby under a tension controlled by the speed of the rolls to the bight of the winding drum and spool. This insures an even winding under uniform tension of the yarn on the spool and in practice enables a larger quantity of yarn to be wound on the spool than has heretofore been the practice. It is in fact practical, with the accurate control thus obtained by this invention, to wind the yarn on the spool so that the diameter of the yarn mass is substantially greater than the diameter of the spool heads.

The transfer of the draft on the yarn ends, required to deliver them to the spool, from the winding drum and spool to the measuring and feed roll and its cooperative top roll, and the accuracy with which the tension is controlled, enable these highly desirable results to be secured. The specific means illustrated, but to which the invention is not restricted, for adjusting the speed of the measuring and feed roll 16 is a standard mechanical device, namely, ad-

justable V-grooved pulleys for the V-shaped belt 42. The pulley 18 is illustrated as thus adjustable and the same construction may be applied to the pulley 47. As shown in Fig. 10 the pulley 18 is formed in two sections, the section 50 being secured to the shaft 17 of the measuring and feed roll, and the section 51 having the hub 52 fitting over and adjustable upon the hub 53 of the section 50 and adjustable thereon. Thus the V-shaped belt 42 may be adjusted to travel slightly nearer to or further from the periphery of the pulley and thus accurately adjust the speed of the feed and measuring roll.

The adjustment provided for the cooperating top roll as by means of the set screws 23 enables just sufficient pressure to be placed upon the yarn ends to secure the required feeding function and maintain the required tension between the feeding and measuring roll and the yarn as it winds upon the spool.

The mechanism employed in this invention for maintaining a constant and required pressure of yarn mass of the spool upon the winding drum is operated by fluid under pressure and preferably pneumatically or by compressed air and the same mechanism is also arranged to provide for the ready doffing of the fully wound spool and the replacement upon the winding drum of the empty spool.

At the rear of the machine a suitable framework is provided for supporting both the supply of empty spools and a group of the wound spools. This framework essentially is provided with a pair of parallel tracks 60 extending from adjacent the top of the winding drum and sloping slightly rearward. These tracks receive the wound spools. Suitable removable abutments 61 at the rear end of the tracks 60 limit the rearward movement of the wound spools.

This framework is also essentially provided with another pair of grooved tracks 62 mounted above the tracks 60 and sloping slightly forward, and in the grooves of these tracks 62 rest the heads of the supply of empty spools. A shaft 63 extends through the forward ends of the tracks 62 and has mounted thereon curved grooved abutments 64 constituting prolongations of the track 62. These abutments are normally held by the spring 65 in elevated position and thus support the foremost empty spool in position to be discharged into engagement with the driving drum.

The gudgeons 66 of the spool being wound rest in the upper seats of spool supports 67 secured to and projecting downward from an arm 68, one at each side. These spool supports also are shaped at the bottom to form gudgeon-supporting seats 69 and 70. From the rearward seats 70 the supports open rearward to permit the gudgeons to move into and out of the supports.

A shaft 71 extends through and is journaled in the upper ends of the side frame members 1 and 2. The arms 68 are secured to this shaft, and at the outer side of the frame member 1 an operating arm 72 is secured to this shaft. Adjacent the arm 68 an upwardly extending arm 73 is journaled on the shaft 71 and is connected by a link 74 with the arm 75 secured to and extending upward from the shaft 63. A pickup arm 76 is secured to and rotarily adjustable upon the shaft 71 as by means of a set screw 77. This pickup arm 76 extends around behind the arm 73 and consequently will act to engage and move the arm 73 forward when a sufficient

upward movement is given to the operating arm 72.

As previously set forth, important features of the invention reside in the novel means for securing and maintaining a constant predetermined pressure of the spool or the yarn mass being wound thereon against the surface of the driving drum, and in the novel means for securing the ready doffing of the wound spool and the replacement of an empty spool. For these purposes the invention provides fluid, and preferably pneumatic, actuated and controlled mechanisms preferably acting to effect the desired results through movement of the operating arm 72.

In the preferred construction illustrated, a cylinder 80 is pivotally mounted at 81 at its lower end to a bracket 82 secured to and projecting outwardly from the side frame member 1. A piston 83 in the cylinder is provided with a piston rod 84 extending through the upper end of the cylinder and pivotally connected at 85 to the end of the operating arm 72. A suitable source of compressed air is supplied to a pipe 86. This pipe contains a standard pressure reducing valve 87 which is set to maintain the required pressure, and this pressure is indicated upon a suitable pressure gauge 88 connected in the pipe 86. From the pressure gauge the pipe 86 extends to and is connected to the main controlling valve 89 provided with an operating handle 90 and located at the front of the frame of the machine in a position convenient to the operator. This valve is provided with two exit ports, one connected by the pipe 91 to the upper end of the cylinder, and the other by the pipe 92 to the lower end of the cylinder 80. By operating the handle 90, the compressed air may thus be connected to either end of the cylinder. Both of the pipes 91 and 92 are provided with standard speed regulating valves 93 set to prevent any sudden movement of the piston 83 and the pipe 91 extending to the upper end of the cylinder is provided with a relief valve 94 set just above the pressure in the cylinder to balance the pressure predetermined by the gauge 88 and reducing valve 87 thus preventing building up of pressure in the cylinder during the operation of the machine.

At the beginning of the winding operation the parts are in the position shown in Fig. 5, and the operator has turned the main valve to cause the pressure to be applied through the pipe 91 to the top of the piston. Since this pressure is maintained constant at a pre-determined amount, the yarn is wound under steady pressure as the gudgeons 66 of the spool gradually, through the mechanism indicated, move the piston upward. When the winding operation has been completed, the parts are in the position shown in Fig. 6 and during the entire winding operation, the gudgeons 66 are pressed into the uppermost seat of the recess in each spool support or spool holder 67.

The operator now has to cut and tie the ends. To enable this readily to be done, the operator turns the main valve to cause the pressure to be applied beneath the piston until, as it moves, the spool support 67, the gudgeons 66 drop into the lower rearward seats 70 as shown in Fig. 8 and are lifted thereby slightly to clear the yarn mass of the spool from the winding drum.

When the ends have been tied and the filled spool is ready to be doffed or discharged from the machine, the operator operates the main valve to allow the piston to move down slightly 75 causing the periphery of the yarn mass to rest

upon the winding drum periphery and thereupon the filled spool rolls out of the spool holders or supports 67 on to the tracks 60.

The operator then operates the main valve to cause the piston to move upward to its extreme upper position. This brings the spool supports or holders 67 into a position illustrated in Fig. 9 and at the same time the pickup arm 76 has acted to swing the upwardly extending arm 73 to the right and move the curved abutments 64 into the position illustrated in Fig. 9. The parts are so proportioned that when they reach these positions, the empty spool standing on the forwardly sloping tracks 62 rolls down the curved abutments 64 and its gudgeons land in the seats 70 and finally roll into the forward seats 69. The operator then turns the main valve causing the piston to move downward and the empty spool to be brought into winding position as indicated in Fig. 5, the gudgeons then rising as the spool core comes in contact with the winding drum into the upper seats in the spool holders 67.

The machine is readily controlled by the operator. The main valve is conveniently located at the front near the center, and adjacent to it is conveniently placed the switch box 100 for controlling the motor. As illustrated it is provided with three controls 101, one for starting and one for stopping the motor, and one for what is known as "inching" enabling the motor to move slightly and stop as is often required in such mechanism.

The knob 10, by which the speed of the spooler is regulated, is also within easy reach of the operator. The means for adjusting the position of the cooperating roll 19 with respect to the feed roll 16 is also positioned where it may be readily reached and operated. In fact all of the elements requiring any adjustment or regulation are positioned for ready manipulation by the operator. Thus the machine is under perfect control with respect to all of its functions.

Since the yarn ends are wound under constant pressure and with an even regulated tension the yarn mass is built up into uniform compact form and as a result the maximum yardage is wound into the yarn mass onto the spool and in practice the diameter of the yarn mass may, and frequently is, wound to exceed the diameter of the spool heads.

Having thus described the invention, what is claimed as new, and desired to be secured by Letters Patent, is:

1. In a spooler having a driven drum on which the yarn mass rests and is wound thereby onto a spool, a feed roll mounted in front of and parallel with the drum, a cooperating roll for the feed roll between which and the feed roll the yarn ends pass to the bight of the drum and spool, and means for driving the feed roll to cause the yarn ends to be fed by it and the cooperating roll to the bight of the drum and spool, the provision of mechanism for relatively adjusting the feed roll and cooperating roll to maintain the peripheries thereof out of contact but sufficiently close to pinch the yarn ends passing therebetween.

2. In a spooler having a driven drum on which the yarn mass rests and is wound thereby onto a spool, a feed roll mounted in front of and parallel with the drum, a cooperating roll for the feed roll between which and the feed roll the yarn ends pass to the bight of the drum and spool, and means for driving the feed roll to cause the yarn ends to be fed by it and the co-

operating roll to the bight of the drum and spool, the provision of mechanism for bodily adjusting the cooperating roll toward the feed roll to a position where the periphery of the cooperating roll is out of contact with the periphery of the feed roll but sufficiently close thereto to pinch the yarn ends passing between the rolls.

3. In a spooler having a driven drum on which the yarn mass rests and is wound thereby onto a spool, a feed roll mounted in front of and parallel with the drum, a cooperating roll for the feed roll between which and the feed roll the yarn ends pass to the bight of the drum and spool, and means for driving the feed roll to cause the yarn ends to be fed by it and the cooperating roll to the bight of the drum and spool, the provision of arms one at each end of the cooperating roll in which the said roll is journaled, and a set screw in each arm engaging the frame of the spooler adjustable to position the said roll with its periphery out of contact with the periphery of the feed roll but sufficiently close thereto to pinch the yarn ends passing between the rolls.

4. In a spooler having a driven drum on which the yarn mass rests and is wound thereby on a spool having heads and gudgeons extending beyond the heads, the combination of a shaft journaled above and parallel with the drum, a pair of arms secured to the shaft, gudgeon supports on the arms having open bearings for the gudgeons, a track to support wound spools extending rearward and downward from the winding position of the spool, a second track to support empty spools above the first track sloping forward and downward, and a power operated means connected to the shaft operable either to maintain the spool pressed against the drum during the winding operation or to raise the arms to a position to allow the wound spool to roll out of the open bearings onto the first track or to raise the arms to a higher position to allow an empty spool to roll from the second track into the open bearings.

5. In a spooler having the construction and combination defined in claim 4, curved abutments pivoted at the forward end of the second track and a connection therefrom operated by the shaft normally to hold the abutments raised limiting forward movement of an empty spool on the track and to lower the abutments, when the arms are raised to the higher position, to support and guide the empty spool as it rolls into the open bearings.

6. In a spooler having a driven drum on which the yarn mass rests and is wound thereby on a spool having heads and gudgeons extending beyond the heads, the combination of spool supports having bearings engaging the gudgeons, a cylinder and piston connected the one to the spooler frame and the other to the spool supports, a main valve, and piping connections from a supply of compressed air to the valve and between the valve and each end of the cylinder acting upon operation of the valve to cause the compressed air to press the spool against the drum throughout the winding operation and thereafter to release the said pressure.

7. In a spooler having a driven drum on which the yarn mass rests and is wound thereby on a spool having heads and gudgeons extending beyond the heads, the combination of spool supports having bearings engaging the gudgeons, a cylinder and piston connected the one to the spooler frame and the other to the spool supports, a main valve, a main pipe for supplying compressed air to the main valve, a pipe from the main valve to one end of the cylinder, a pipe

from the main valve to the other end of the cylinder, the said valve acting in one position to cause the compressed air to press the spool against the drum and acting in a second position to cause the compressed air to raise the spool above the drum.

8. In a spooler having a driven drum on which the yarn mass rests and is wound thereby on a spool having heads and gudgeons extending beyond the heads, the combination of spool supports having bearings engaging the gudgeons, a cylinder pivoted at its lower end to the spooler frame, a piston in the cylinder with a piston rod connected to the spool supports, a main valve connected to a supply of compressed air and to each end of the cylinder and operable to connect the compressed air to either end of the cylinder.

9. In a spooler having the construction and combination defined in claim 8, a speed regulating valve in each connection from the main valve to the cylinder.

10. In a spooler having the construction and combination defined in claim 8, a relief valve in the connection from the main valve to the upper end of the cylinder to prevent building up of pressure during the winding operation.

11. In a spooler for winding a plurality of yarn ends upon a spool comprising a support at the rear for holding a wound spool, a second support at the rear for holding an empty spool, and mechanism including a cylinder and piston, a main valve, and piping connections from a supply of compressed air to the valve and between the valve and each end of the cylinder acting by operation of the valve to effect transfer of a wound spool from its winding position to the first support and thereafter to effect transfer of an empty spool from the second support to winding position.

12. In a spooler having a driven drum on which the yarn mass rests and is wound thereby on a spool having heads and gudgeons extending beyond the heads, the combination of a shaft journaled above and parallel with the drum, a pair of arms secured to the shaft, gudgeon supports on the arms having open bearings for the gudgeons, a track to support wound spools extending rearward and downward from the winding position of the spool, a second track to support empty spools above the first track sloping forward and downward, a cylinder and piston connected the one to

5

10

the frame of the spooler and the other to said shaft, means for supplying compressed air to the opposite ends of the cylinder and means for controlling the supply of compressed air to cause the relative movement of the cylinder and piston either to press the spool against the drum throughout the winding operation or to raise the arms to a position to allow the wound spool to roll out of the bearings onto the first track or to raise the arms to a higher position to allow an empty spool to roll into the bearings.

13. The combination in a spooler having a winding drum on which the yarn mass rests and is wound thereby onto the spool of a spool-supporting frame comprising a pair of parallel tracks extending rearward and downward from the winding position of the spool to receive the wound spools, and a pair of grooved tracks above the aforesaid tracks sloping forward and downward to support therein the heads of empty spools and having at their forward ends grooved abutments normally acting to limit forward movement of the empty spools and movable into position to allow the foremost empty spool to roll into position to be received by the spooler.

14. The combination defined in claim 13, together with an element connecting the said abutments to the spooler and actuated thereby to move the said abutments into position to allow the foremost empty spool to roll into position to be received by the spooler.
